(57) **CLAIM**

The ornamental design for a handle for rotary tool, as shown and described.

DESCRIPTION

FIG. 1 is a top left perspective view of the present new design for a handle for rotary tool;

FIG. 2 is a top plan view thereof;

FIG. 3 is a bottom plan view thereof;

FIG. 4 is a left elevational view thereof, the right elevational view being a mirror image therof;

FIG. 5 is a front elevational view thereof; and,

FIG. 6 is a rear elevational view thereof.

The broken lines showing various features of a handle for rotary tool are for illustrative purposes only and form no part of the claimed design.
